UNITED STATES PATENT OFFICE.

THOMAS M. NORTH, OF LONDON, ENGLAND, ASSIGNOR TO LINOTYPE AND MACHINERY LIMITED, OF LONDON, ENGLAND.

PRINTING-MACHINE.

No. 815,857.

Specification of Letters Patent.

Patented March 20, 1906.

Application filed June 23, 1905. Serial No. 266,610.

To all whom it may concern:

Be it known that I, THOMAS MERRIFIELD NORTH, of 188 and 189 Fleet street, London, England, have invented new and useful Improvements in Printing-Machines; and I do hereby declare the following to be a full, clear, and exact description of the invention, such as will enable others skilled in the art to which it appertains to make and use the same.

This invention relates to printing-machines, particularly those of the type known as "aluminium" rotary machines, because their printing-plates demand the constant surveillance of the printer to keep them in perfect printing condition; and the object of it is to provide means whereby the printer is capable of effecting both this surveillance and that of the sheets as they are printed from one and the same position, this provision enabling him by such inspection of the sheets to readily ascertain the condition of the printing-plate and how it is doing its work.

Heretofore in consequence of the efficient inspection of the form-cylinder being possible only from the rear side of it at one end of the machine and that of the printed sheet being possible only at the other end of the machine (because the delivery has always been at that end) it has been necessary for the printer to walk from the cylinder to the delivery-board to ascertain by inspection of the printed sheet thereon the working condition of the printing-surface and then to walk back again to the cylinder to remedy any defects thereon the existence of which have been disclosed by the last-named inspection.

Now the present invention obviates the necessity of the printer walking from the cylinder to the delivery-board and back again, because it places the delivery-board at the rear side of the form-cylinder and so near to it that the printer can inspect them both without any appreciable change of position, for according to the said invention he is now able to stand with one shoulder turned to the printing-cylinder and the other turned to the delivery-table, whereby by merely turning his head from left to right and right to left he can with ease make the desired inspection.

The accompanying drawing, which is to

be taken as part of this specification and read therewith, is a side elevation of a printing-machine arranged according to the present invention, the sheet-delivery mechanism being represented in dotted lines.

In carrying the said invention into effect a multiple-revolution impression-cylinder 1 is employed, because this type of cylinder contributes to the maintenance of the printed-side-up position of the sheet and to the prevention of that face of the sheet coming into contact with any member of the delivery mechanism. This cylinder, as ordinarily, receives the sheets to be printed from the feed-board 2 and is supported in adjustable bearings 3, mounted in the side frames 4 of the machine, only one of which frames is represented in the drawing. The impression-cylinder 1 co-operates with the form or printing cylinder 5, which is also, as ordinarily, mounted in the frames 4 and provided with the necessary inking mechanism 6 and damping mechanism 7. The sheets after receiving their impression are taken from the impression-cylinder 1 by a guide 8, which conducts them to the downwardly-inclined carrier-tapes 9, which in turn deliver them to another guide 10, whence they pass to the delivery-chains or equivalent 11. The carrier-tapes 9 travel around two cylinders 12 13, the latter of which is positively rotated by gearing with a spur-wheel 14, which also is in operative gear with wheels or pulleys 15, (only one of which is indicated in the drawing,) about which the forward parts of the delivery-chains 11 pass. From these forward parts the chains 11 extend rearward below a platform 16 on which the printer is stationed, and at the rear of this platform the chains are guided upward by guides 17, whence they pass over rollers 18, situated at the front of the delivery-board 19, and thence rearward over the said delivery-board to rollers 20. From these rollers 20 the delivery-chains 11 pass downward to rollers 21, from which they pass in a forward direction to the before-mentioned wheels or pulleys 15. The chains 11 are provided with any of the well-known arrangements of grippers, these being adapted to grip the sheets as the latter pass over or are leaving the guide 10 and to release the said sheets when they are over the

delivery-board 19 to allow them to drop, printed side up, onto the said board. These grippers are not represented in the drawing, because they constitute no part of the present invention.

It is to be observed that by the foregoing arrangement the printed-side-up delivery is effected without the use of any transferring or reversing cylinder or any similar devices capable of touching the printed sides of the sheets.

The height of the platform 16 relatively to that of the form-cylinder 5 is preferably practically the same as that of the floor to the form-cylinder in existing machines, this disposition being preferred, so as not to interfere with the working position of the printer as inspector and toucher-up of the printing-surface. The distance of the delivery-board 19 from the form-cylinder 5 and the height of it above the platform 16 are such that the printer has room enough to do his work on the printing-surface, as well as examine the printed sheets as they are delivered onto the board 19. It is proposed to provide a seat upon the platform 16, so that the printer when seated thereon and facing toward one or other side of the machine may by merely turning his head to right or left of him readily inspect the cylinder 5, on the one hand, and the topmost of the printed sheets 22, on the other hand. At the back of the platform is provided a guard or screen 23 to prevent the printer from coming into accidental contact with the sheet-delivery mechanism or the sheets being delivered.

It will be readily understood that by suitably arranging the form-cylinder 5 and the delivery-board 19 as regards their respective heights from the floor and arranging the delivery-chains to dip down beneath the floor between the said form-cylinder and delivery-board a special platform, such as that shown in the drawing, need not be provided, the portion of the floor between the form-cylinder and delivery-board in such an arrangement serving to fulfil all the necessary functions of the said platform. For this reason the term "stand" as hereinafter employed is intended to include any such platform or device situated between the form-cylinder and the delivery-board as will enable the printer when stationed thereon to freely inspect the form and printed sheets, as aforesaid, without moving from one part of the machine to another.

Subject to the sheet-delivery mechanism being such as to conduct the printed sheets beneath the stand situated between the form-cylinder and the delivery-board at which the printer is stationed and to deliver the sheets on the delivery-board printed side up, any

construction of delivery mechanism other than that herein previously described may be employed.

I claim—

1. In a printing-machine, the combination of a form-cylinder, a feed-board and delivery-board at respectively opposite sides of the said cylinder, and a stand for the printer, between the form-cylinder and delivery-board. 65

2. In a printing-machine, the combination of a form-cylinder, a feed-board and delivery-board at respectively opposite sides of the said cylinder, a stand for the printer, between the form-cylinder and delivery-board, and sheet-delivery mechanism adapted to deliver the printed sheets, printed side up, onto the delivery-board. 70

3. In a printing-machine, the combination of coöperating form and impression cylinders, a delivery-board, a stand for the printer, between the delivery-board and the form and impression cylinders, and sheet-delivery mechanism adapted to conduct the printed sheets from the impression-cylinder, beneath the stand, and deliver them, printed side up, on the delivery-board. 80

4. In a printing-machine, the combination of an impression-cylinder, a delivery-board, a stand for the printer between the impression-cylinder and delivery-board, and sheet-delivery mechanism adapted to conduct the printed sheets from the impression-cylinder beneath the stand and deliver them printed side up on the delivery-board. 90

5. In a printing-machine, the combination of a form-cylinder, a delivery-board and a stand for the printer between the said cylinder and board, the respective heights of the cylinder, board and stand being such that when the printer is stationed on the stand he can, without shifting his position, readily inspect the form and the printed sheets. 100

6. In a printing-machine, the combination of a form-cylinder, a feed-board and delivery-board at respectively opposite sides of the said cylinder, a stand for the printer, between the form-cylinder and delivery-board, and sheet-delivery mechanism adapted to conduct the printed sheets beneath the stand, and deliver them, printed side up, on the delivery-board. 105

7. In a printing-machine, the combination of coöperating form and impression cylinders, a feed-board and delivery-board at respectively opposite sides of the said cylinders, a stand for the printer, between the delivery-board and the cylinders, and sheet-delivery mechanism adapted to conduct the printed sheets from the cylinders, beneath the stand, and deliver them, printed side up, on the delivery-board. 115

8. In a printing-machine the combination

of coöoperating form and impression cylinders, a delivery-board, a stand for the printer, between the delivery-board and the form and impression cylinders, sheet-carriers adapted 5 to conduct the printed sheets from the form-cylinder to below the stand, and delivery devices adapted to take the sheets from the carrier-tapes, conduct them below the stand

and raise them above, and drop them onto, the delivery-board. ¹⁰

In witness whereof I have hereunto set my hand in the presence of two witnesses.
